REVERSIBLE SEAT BASE

Oiva E. Hill, Gardner, Mass., assignor to Heywood-Wakefield Company, Gardner, Mass., a corporation of Massachusetts

Application October 27, 1938, Serial No. 237,233

6 Claims. (Cl. 155—96)

This invention relates to reversible car-seat bases of the cam-controlled type which rotate from one position of use to the other about a vertical axis and which are automatically shifted 5 away from the adjacent wall of the car or other vehicle in which they are mounted during the initial portion of their reversing movement from either position of use. The purpose of such shifting movement toward the aisle is to enable the 10 seats to be located very close to the wall of the vehicle and yet to be reversed without interference between the corners of the seat and the wall, thus providing maximum aisle space when the seats are in use.

15 The reversing mechanism hereinafter described is a modification of or improvement over the mechanism described in my application Serial No. 200,825, filed April 8, 1938. The mechanism therein described gives to the seat not only an 20 endwise motion away from the wall but also a considerable front-and-rear motion as well. According to the present invention, this front-and-rear movement is materially reduced with relatively little reduction in the movement of the seat 25 away from the wall.

Another object of the present invention is a smoother reversing movement than that of the earlier mechanism. The present invention also includes improved means for holding the seat 30 reversably not only in its normal positions of use but also in a half-way position in which the seat may face the wall or the aisle, depending upon the manner in which the seat is mounted on its carrier.

35 For a more complete understanding of the invention, reference may be had to the following description thereof, and to the drawings of which—

Figure 1 is an end elevation of a car seat or 40 chair.

Figure 2 is a fragmentary floor plan view of a vehicle showing the arrangement of seats or chairs embodying the invention.

Figure 3 is a section on the line 3—3 of Figure 2, 45 on a larger scale.

Figure 4 is a section on the line 4—4 of Figure 3.

Figure 5 is a section on the line 5—5 of Figure 3.

Figure 6 is a section on the line 6—6 of Figure 3, on a smaller scale.

50 Figure 7 is a view similar to Figure 6 showing additional elements.

Figure 8 is a view similar to Figure 7, showing the parts in a different position of operation.

Figure 9 is a section on the line 9—9 of Figure 55 8, on a larger scale.

Figure 10 is a geometric diagram to illustrate the operation of the cams.

The chair shown in Figure 1 includes a base or pedestal 10 which is secured to the floor of the vehicle. On this base is supported a seat 12 which is provided with a back 14 and one or more arm rests 16. As indicated in Figure 2, the seat may be a double seat consisting of two individual units separated by an arm rest. The invention, however, may be embodied in other varieties of single or double reversible seats. Figure 3 illustrates a reversing seat support or base on which a seat of any desired kind may be mounted. This base is in the form of a pedestal 20 having a flat top plate 22 on which the seat is slidable. Instead 10 of the pedestal any other preferred form of base or support may be employed having a horizontal surface on which the seat is slidable. In order to 15 guide the reversing movement of a seat so that the arm rests and backs of the seats will clear the wall of the vehicle when the seat is turned, guiding mechanism such as is illustrated in Figures 3 and 6 is provided. As shown, this guiding mechanism 20 comprises a pair of cam followers 24 and 26 which may conveniently be in the form of rollers 25 rotatable on vertical stems 28 and 30 respectively. These stems project upward from a spacer bar 32 located beneath the plate 22, and, in the assembled chair, are secured to the frame of the seat 12. The bar 32 cooperates with the seat 30 frame to maintain the cam followers or rollers 24 and 26 at a constant distance apart.

As indicated in Figure 6, the rollers 24 and 26 bear against and are guided by cam edges which define an aperture 34 in the plate 22. These cam 35 edges are in the form of a closed curve which is symmetrical with respect to the longitudinal median of the base. Immediately below the rollers 24 and 26 are discs 35 of larger diameter, these discs having portions projecting under the 40 margins of the plate 22 along the cam edges so as to act as hold-down members for the seat 12. The cam edges consist of a pair of arcuate portions 36 and 38 which are of equal length and curvature and are tangent respectively to the 45 rollers 24 and 26 when the latter are in their normal positions, the center of curvature of the arc 36 being in the axis of the stem 30, that is, the center of the roller 26, the center of curvature of the arc 38 being on the axis of the stem 28, that is, the center of the roller 24. The corresponding opposed ends of these two arcuate portions of the cam edge are connected together by two arcuate edge portions 40 and 42 of unequal 50 length and curvature. The latter arcs are struck 55

from a common point on the longitudinal median of the base, the position of this point being determined by the length of the arcuate edge portions 36 and 38 as hereinafter explained in connection with the description of Figure 10. The 5 arc 40 meets each of the arcs 36 and 38 at a considerable angle, the intersections being rounded to form corners in which the rollers 24 and 26 fit when in normal position. The arcs 40 and 42 10 are both bisected by and symmetrical with respect to the longitudinal median of the base. Both of these arcs have a greater curvature than the arcs 36 and 38.

Referring to Figure 10 for an explanation of 15 the geometrical relation between the various portions of the cam in comparison with the cam described in my said application Serial No. 200,825, A and B represent the centers of the rollers 24 and 26 when the seat is in one of its 20 normal positions of use. The cam portion BC is struck with A as a center and represents the path of initial movement of the roller when the seat is being reversed. In like manner, the cam portion AD is struck with B as the center and 25 represents the final movement of the roller 26 when the seat is reversed. If these arcs are continued to intersect at E, as indicated in light lines, the arcs CE and ED represent the path of movement the roller 26 would have from C to D 30 if the cam edge were shaped as described in my said application Serial No. 200,825. In such case, the roller 24 would follow an arc AFB while the roller 26 paused at E, the arc AFB being struck with E as its center. According to the present 35 invention, the roller 26 is made to follow the arc CJD in moving from C to D, and the roller 24 moves along a path indicated by the arc AHB. The line AC represents the position of the bar 32 when the roller 26 reaches the end of the arc 40 BC. The line BD represents the position of the bar 32 when the roller 26 is at the end of the arc AD. The intersection G of these two lines is the center of curvature of the arcs CJD and AHB. It is evident that, since every point of 45 the arc AHB is equally distant from the center G and since every point of the arc DJC is equally distant from the center G, the rollers 24 and 26 follow the arcs indicated in dark lines in Figure 50 10 during a reversal of the seat. Thus, while the roller 24 remains stationary at A, the roller 26 moves from B to C. The roller 24 then leaves the point A and moves along the arc AHB as the roller moves along the arc CJD, the spacer bar 32 rotating about the point G until it reaches 55 the position indicated by the line BD. Thereupon the roller 24 remains at B while the roller 26 moves from D to A to complete the reversing movement of the seat. When the seat is reversed in the opposite direction, these movements of 60 the rollers take place in the reverse order. As a result of any reversing movement, the centers of the rollers 24 and 26 exchange places. During the reversing movements, the seats will face either the wall or aisle of the vehicle according to 65 the manner in which they are secured to the guiding mechanism. Thus, if a seat is secured to the stems 28 and 30 so that it faces to the left when the rollers 24 and 26 are in the positions indicated in Figures 6 and 7, the seats 70 will face the wall during reversing movements since the bar 32 swings in a clockwise direction from the position shown in those figures. If, however, the seat is secured to the stems so that it faces toward the right when the rollers 24 and 75 26 are in the positions shown in Figures 6 and 7,

then the seat will face the aisle during the reversing movements.

The diagram in the central portion of Figure 10 indicates the path of movement of the center point of the spacer bar 32, which is preferably 5 directly below the center point of the seat 12. The point K is the position of the center of the spacer bar 32 when the seat is in either of its normal positions of use. As the bar swings about A as a pivot, its center moves to the 10 point L. During the rotation of the spacer bar about the point G, its center moves along the arc from L to M. During the final movement of the spacer bar about B as a pivot, its center moves along from M to K. In installing a 15 seat base of this type in a vehicle, the base is arranged so that the point H is toward the wall of the vehicle, the point E being toward the aisle. Thus the broken line KN represents the displacement of the center of the seat away 20 from the wall of the vehicle during the initial portion of the reversing movement. The line NL likewise represents the displacement of the center of the seat in a front-and-rear direction during such initial portion of the reversing 25 movement. For purposes of comparison, the arm KL is extended to P to represent the movement of the seat center when a three-cornered cam edge, such as is described in said application Serial No. 200,825, is employed, the remainder of the movement of the center being 30 along the arcs PR and RK to complete the reversing movement of the seat. The broken line PR indicates the front-and-rear displacement of the seat center from the median line 35 KS during the reversing movement. It is evident from this figure that the use of a cam made according to the present invention results in a marked reduction in the front-and-rear displacement of the seat center with a considerably 40 smaller reduction of displacement away from the wall of the vehicle. This result is highly desirable since the quick movement away from the wall is retained without being accompanied by excessive front-and-rear movement 45 which would tend to cause interference between the corners of the seat and the front or rear portions of adjacent seats in the vehicle.

To assist the cam edges to function properly in guiding the cam followers as described and to minimize side-lash of the seat carriage during 50 reversing movement thereof, auxiliary means are provided for shifting the axis of rotation of the seat carriage to a point between the followers, which point serves as a pivot for the carriage 55 during the mid-portion of its reversing movement in either direction. To this end the spacer bar 32 may be provided with a lug 50 which is adapted to engage in a notch 52 formed in a cross bar 54 secured to the base as indicated in Figure 9. The lug 50 preferably projects down 60 below the spacer bar so as not to interfere with the movement of the cam followers 24 and 26. The notch 52 is located on the longitudinal median of the base at a point corresponding to the 65 point G of Figure 10. When the lug 50 reaches the notch 52 in the course of a reversing movement of the seat carriage, the axis of rotation of the carriage thereupon shifts away from the cam follower 24 and the lug 50 serves as a temporary 70 pivot during the portion of the reversing movement in which the spacer bar moves from a position indicated by the line AC in Figure 10 to a position indicated by the line BD. At this moment the follower 24 reaches the other corner of 75

the aperture 34 and the axis of rotation of the carriage shifts back to it for the remainder of the reversing movement.

Figures 3, 4 and 5 illustrate means for stopping the seat in its normal positions for use and maintaining the seat releasably in such positions. Such means include a pair socket members 60 and 62, which, as indicated in Figure 3, may be secured (as by welding or riveting) to the pedestal itself. Each of these socket members is provided with a concave arcuate recess or socket 64 in which, as indicated in Figure 5, is a projecting lug or stop 66. Cooperating with the recesses 64 are a pair of end members 70 and 72 which are mounted at the ends of the tubular spacer bar 32 and which have fan-shaped end portions 74 with a curvature to fit in the recesses 64 when the seat is in either of its normal positions of use. As shown in Figure 5, the fan-shaped portions 74 engage the recesses 64 at a level just above the lugs 66. Below the center of the fan-shaped portion 74 of the member 70 is a downwardly projecting lug 76 which is on the same level with the lug 66 so that it is stopped by the lug 66 when the spacer bar is in the position shown in Figure 4. The end member 70 may be permanently secured by welding or otherwise to the spacer bar 32, as indicated in Figure 4, or may be yieldingly mounted as indicated in Figure 9. The end member 72 is yieldingly mounted at the other end of the spacer bar. The fan-shaped portion 74 of this end member is adapted to slide in a pair of longitudinal slots 78 extending from the end of the spacer bar, and the sliding movement of the member 72 may be limited by a pin 80 which slides in a slot 82 in the bar. Within the bar a compressed spring 84 presses the member 72 outward, the inner end of the spring 84 bearing against a transverse pin 86. The spring 84 presses the convex end of the end member 72 into the recess 64 to hold the seat yieldingly in a position for use. When it is desired to reverse the seat, the arm or back of the seat may be given a quick pull to cause the member 72 to ride out of the recess 64. The seat is then reversed on the pedestal, its movement being guided by the cam followers 24 and 26 engaging the cam edges as hereinbefore described. This movement results in the end member 70 entering the recess 64 which has just been vacated by the end member 72, the lug 76 engaging the stationary lug 66 to prevent movement of the end member 74 beyond the recess. As the seat reaches its reversed position, the spring 84 yields to permit the member 72 to ride into the recess 64 which has been vacated by the member 70. Thus the seat is held releasably in reversed position.

If it is desired to retain the seat in an intermediate position of use wherein the seat faces either the wall of the vehicle or the aisle, the stationary socket member 90 is mounted on the pedestal so as to be engaged by the end member 70 when the seat is in its mid position between the normal positions of use. In order to retain the seat in its mid position, it is preferable to employ the fixed transverse member 54 with its notch 52 in which the lug 50 engages when the seat is in its mid position. Since the lug 50 is unyielding, the end member 70, instead of being fixed within an end of the spacer bar, is slidably positioned therein and is outwardly pressed by a spring 92 bearing against a pin 94, as shown in Figure 9, the movement of the end member being limited by a pin 96 which slides in a slot 98. The end member 70 is thus mounted in the same man-

ner as the end member 72 and may be similar to the latter except for the lug 76.

It is evident that various modifications and changes may be made in the embodiment of the invention herein shown and described without departing from the spirit or scope thereof as defined in the following claims.

I claim:

1. In a reversible seat base mechanism, a horizontal stationary plate on which a seat is slideable, said plate having an aperture defining a cam edge in the form of a closed curve consisting of four circular arcs, two of said arcs being of equal length and curvature and alternating with the other two which are of different curvature but are struck from a common center, and a guide member for said seat including a pair of cam followers engaging said cam edges at opposite sides of said aperture, and spacing means for said cam followers. 15

2. A reversing car-seat base comprising a stationary pedestal with a horizontal top, a seat carriage slidably supported on said horizontal top, said top having an aperture therein defining cam edges, a pair of cam followers spaced a fixed 20 distance apart and attached to said seat carriage, said aperture having a pair of corners occupied by said followers when the carriage is in either of its positions for use and a pair of arcuate edge portions adjacent to respective corners whereby one of said followers acts in its 25 corner as a pivot for the carriage during the initial portion of a reversing movement of the carriage and acts in the other corner as a pivot for the carriage during the final portion of said 30 reversing movement, and means operative during the intermediate portion of the reversing movement to shift the axis of rotation of the carriage to a point between the two said followers and to shift said one of said followers from 35 its corner to said other corner. 40

3. In a reversible seat base mechanism, a horizontal stationary plate having an aperture therein defining a cam edge in the form of a closed curve consisting of a pair of arcs of different 45 curvature struck from a common center on the longitudinal median line of the base and bisected by said line, and another pair of arcs of equal length and curvature connecting respective ends of the first said arcs, a pair of cam followers simultaneously engaging opposite portions of said 50 curve, and means for maintaining said cam followers constantly spaced apart, said spacing means being attachable to a seat on said plate whereby said cam followers and spacing means 55 move with the seat and guide the movement thereof.

4. In a reversible seat base mechanism, a stationary member having an inner cam edge in the form of a closed curve symmetrical with respect to the longitudinal median of the base, said cam edge having two arcuate portions of equal length and curvature on opposite sides of said median and two arcuate portions of different length and curvature struck from a common center on said median and joining the ends of said equal portions, a pair of cam followers engaging said cam edge, means including a spacer bar for maintaining said cam followers at constant distance apart, means releasably holding 65 said cam followers at the junctures of the longer of the unequal arcs with the equal arcs, a lug on said spacer bar between the ends thereof and movable therewith, said lug being located so that its path of movement crosses said median at 70 75

- said common center, and a stationary member having a recess arranged to receive said lug when it reaches said common center.
5. In a reversible seat base mechanism on a stationary base, a seat-guiding member comprising a pair of cam followers and a spacing bar on which said cam followers are mounted, said cam followers having mutually exchangeable normal positions of rest to the front and rear 10 of the longitudinal median of the base when the seat is in either of its normal positions for use, a lug mounted on said spacing bar between said cam followers, and cam means cooperating with said cam followers and lug to guide the reversing movements of the seat, said cam means comprising a pair of converging arcuate edge cams each tangent at one end to one of said cam followers in normal position and having its center of curvature at the center of the other cam follower, a stationary member having a notch at 15 said median line engageable by said lug during a portion of the reversing movement of the seat whereby said lug serves as a temporary pivot for

the seat, said cam means also including a third arcuate cam edge extending from one normal position of the cam followers to the other and having its center and having its center of curvature in said notch for the lug.

6. In a reversible seat base having a horizontal plate with an aperture therein defining an edge cam, a pair of cam followers engaging said cam at opposite points thereof, and spacing means for maintaining said cam followers at a constant 10 distance from each other, means for releasably holding said cam followers in predetermined positions relative to said cam, said means comprising a pair of abutment elements with arcuate recesses mounted on said base, and a pair of end 15 elements projecting from the ends of said spacing means and having convex extremities fitting said arcuate recesses, one of said end elements being yieldable lengthwise of said spacing means for snap action in engaging with and disengag- 20 ing from either of said recessed abutment elements.

OIVA E. HILL.
